CLAIM

We claim, the ornamental design for a charging inlet cap for an electric vehicle, as shown.

DESCRIPTION

FIG. 1 is a perspective view of a charging inlet cap for an electric vehicle, showing my new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another perspective view from a different angle thereof.
